UNITED STATES PATENT OFFICE.

CARLETON ELLIS, OF MONTCLAIR, NEW JERSEY, ASSIGNOR TO ELLIS-FOSTER COMPANY, A CORPORATION OF NEW JERSEY.

PROCESS OF FORMING OXIDS OF NITROGEN.

1,007,683.

Specification of Letters Patent.

Patented Nov. 7, 1911.

Application filed July 29, 1911. Serial No. 641,365.

To all whom it may concern:

Be it known that I, CARLETON ELLIS, a citizen of the United States, and a resident of Montclair, in the county of Essex and State 5 of New Jersey, have invented certain new and useful Improvements in Processes of Forming Oxids of Nitrogen, of which the following is a specification.

This invention relates to the oxidation of 10 the nitrogen of the air by electrical means, and relates in particular to a specific method of bringing air into contact with an electric arc, whereby a sufficient exposure is secured to said arc to produce a maximum content of oxids of nitrogen all as more fully 15 hereinafter described and claimed.

At the enormously high temperature of 20 the electric arc nitrogen and oxygen apparently dissociate into atoms, and these combine to form nitric oxide as follows:—

This is probably a pure thermal effect and 25 not due to any specific electric effect. That thermal action is sufficient for this reaction is indicated by the work of Bunsen who found that in the explosion of air with hydrogen, oxids of nitrogen formed. Unfortunately, this reaction does not progress to 30 completion. On the contrary, it is very incomplete.

As a purely thermal effect, the simple physico-chemical laws obtain. The law of 35 mass action determines equilibrium and from the above equation we have

$$K = \frac{(NO)^2}{(O_2)(N_2)}$$

40 K. is a constant depending upon the temperature and is independent of the relative amounts of gas at the beginning of the reaction. It is of course important to determine the most favorable temperature for 45 a maximum concentration of nitric oxide. It has been found that at temperatures of 3,000 to 4,000 degrees, combination is extremely rapid. Since, however, the reaction is reversible, it is very important that 50 the gases be quickly cooled after being exposed to such a high temperature. It has been found that at a temperature of 1700° the reaction velocity is so slow that reversion to nitrogen and oxygen is not to be 55 feared.

It has been observed that the output of nitric oxide is smaller, the greater the energy which produces the arc. The electric arc consists of an interior portion which is very hot and an exterior portion, superposed layer, or aureola which is at a lower temperature. Apparently the nitrogen and oxygen combine in the interior portion of the arc and in passing from thence through the aureola are cooled in so gradual a way 60 that a reversal of the reaction occurs. Hence the greater the energy supplied to the arc, the greater the aureola and the more extensive the decomposition of the previously formed nitric oxide. Theoretically 65 therefore, it would be better to use spark discharges, but the energy of a spark discharge is so small that the method is not feasible. Of course with the aid of a system of condensers the current of a spark discharge 70 might be greatly increased, but there are difficulties in the way of carrying out such a plan commercially. Therefore it becomes desirable commercially, to make use of the arc in spite of its disadvantage of 75 aureola decomposition. Output is often more essential than efficiency.

In the treatment of air by its passage across a flaming arc, great difficulty is experienced in maintaining the continuity of 80 the arc, as the air tends to extinguish or "blow out" the arc. In order to secure the rapid cooling effect desired when an intensely hot electric arc, with an extensive aureola is employed, a great excess of air 85 is used, so that the oxids of nitrogen, as soon as formed, will be swept as rapidly as possible out of the aureola zone of decomposition, and cooled by contact with the surrounding air. Hence it follows that the content of oxids of nitrogen at the present time is usually not more than 1% or so of the total air passing through the electrically heated apparatus. This means not only the handling of a great volume of air in the 90 subsequent process of absorption but there is also a tremendous heat loss, due to employing so costly an agent as electric energy for heating up the 98% or 99% or so of air which does not enter into reaction. The 95 sensible heat absorption in this manner is very great and the arc therefore does not work to good advantage under such circumstances. Probably not more than 3% or 4% of the electric energy is absorbed in the 100

actual process of making nitric oxid. Of course a certain portion of this heat is recovered in certain ways, as for example, passing the gases from the electric furnace 5. under steam boilers or evaporating pans, but the generation of heat for such purposes in this way is of course costly, and undesirable.

Besides the flaming arc mentioned above, 10 in which the air travels transversely across the arc, there also exists the method of oxidizing nitrogen, in which air is passed helically about an elongated electric arc and in which case aureola contact is of course 15 pronounced.

The present invention has for its object 20 the production of an arc of great length, so that each furnace or unit of apparatus is capable of handling a great volume of air and in which there is a minimum of aureola 25 contact with respect to the length of the arc. Preferably, for this purpose, I form a long electric arc between two electrodes, or a plurality of electrodes, and cause the air to pass in a circular path in a plane at right 30 angles to the axis of the normal arc passing between the electrodes. Preferably also I take great pains to have the air passing through the apparatus of constant moisture 35 content, so that variations in moisture, such as ordinarily exist in atmospheric air, do not cause variations in the rate of production of oxids of nitrogen. The moisture in the air apparently has no very important 40 bearing on the speed of reaction of the oxidation processes, although it may have a very slight catalytic effect which would be exerted both in causing an acceleration in the speed of combination of oxygen and nitrogen, as well as in the reverse reaction. 45 The essential point is, however, to have the air constant in its content of moisture, and preferably I reduce the content of moisture below that of average humidity, by passing the air over a drying substance, such as calcium chlorid, or I may remove the moisture by refrigeration, to reach a substantially 50 constant moisture percentage.

By reference to the drawings, the manner 55 in which the invention is carried out may be seen.

In the drawings which, for the sake of simplicity, are diagrammatic, Figure 1 shows a side elevation and Fig. 2 an end 60 section of one form of my apparatus. Figs. 3, 4, 5, 6, and 7, show other forms, involving slight structural changes.

Like numerals denote like parts in the several drawings.

In Fig. 1, 1 is a cylindrical furnace chamber, having the water jacket 2, and the electrodes 3, 3. 4 is a flattened portion, serving 65 as an air distributer and heat interchanger. The air, preferably of constant moisture content, enters by the inlet 5, and is injected

into the furnace tangentially as a long, flat, thin stream, which circles about the interior of the furnace, and departs at a point near its entrance. An arc is maintained between the electrodes, and in circling about this arc 70 the air contacts with it, and oxids of nitrogen are formed. Owing to the circular travel of the air, which follows a path at right angles to the axis of the arc, oxidation takes place in such a manner, that there is little opportunity for reverse reaction. In Fig. 3, the apparatus is set horizontally, and an electro-magnet, 7, is arranged to maintain the arc in its normal axis. Fig. 4, shows three inlets, 5, 9 and 10 for the entering air, the outlet being at 6. Fig. 5, shows a chamber of elliptical cross section, having two arcs and provided with means for entering the air tangentially. An electro-magnet is provided at 11, and by the use of an 80 alternating current, the arcs formed at the electrodes, 3, 3', may be caused to vibrate to and fro, using of course, a direct current to form the arc. Fig. 6, shows another form 85 of the apparatus in which the air is entered tangentially on one side and removed on the other side after circulating about the arc in a substantially semicircular path. Fig. 7, shows a cross section of another form in 90 which the air is entered at 5, and the outgoing gases depart through the passage 6. A direct current may be used to form the arc, and a three phase alternating current passed through the coil surrounding the furnace at 14. The air preferably enters the 95 apparatus under considerable pressure, so that a proper tangential whirl may be secured.

The interior of the furnace shell may be lined with difficultly fusible bodies having a catalytic action, and such catalysts as thorium oxid, vanadium oxid, titanium oxid, uranium oxid, boron oxid, aluminum oxid and the like may be applied to the interior 100 of the furnace shell. The exterior of the shell may be water cooled if desired in the manner well known in the furnace art.

In preheating the air supplied to the furnace it will be evident from the foregoing 115 that it is undesirable to use a preheater of so effective a character that the entering gases would have a temperature above the critical temperature of reversion, which as stated is commercially speaking 1700°. It is however, desirable to heat the air as near as possible to this temperature without causing retrogressive changes of a material character. The present process thus secures a 120 large output with a maximum electrical efficiency and a sufficient time contact is secured to derive the necessary heating effect.

With a long arc and an air current traveling from one end of the arc to the other, there is, as stated, unavoidable protracted 125 aureola contact so that the union and decom- 130

position of oxygen and nitrogen may take place an infinite number of times during the long period of travel, resulting in the imperfect application and waste of electric energy. The present process overcomes this difficulty while taking advantage of the commercially valuable features of the long arc.

Electrical energy, derived from water-power or from waste gases of blast furnaces applied to gas engines may be profitably used in carrying out the foregoing process.

The illustrative method herein given depicts the invention in its preferred forms, but it is evident that various modifications may be made in the manner in which the air is caused to circulate about the normal axis of the arc, and the manner in which said arc is caused to travel through the air current, and I do not wish to limit myself to the exact procedure herein described, but may invoke the doctrine of equivalency, so far as same is herein applicable.

Commercial requirements demand the operations involved in the fixation of nitrogen to be carried out on the large scale with apparatus of extreme simplicity and units of great size. The cost of operation and depreciation charges must be very low. The present invention obtains this object in a satisfactory way. The arrangement of air travel provides a minimum of aureola contact with respect to the length of the arc. Direct or alternating current may be used according to circumstances. A direct current ordinarily may be used to advantage when an arc is to be pulsated by magnetic control; an alternating current being used to energize the magnet.

As a matter of commercial exigency, the alternating type of current is usually most readily available, and is therefore more extensively used in electro-thermal operations. The present process is well adapted to be carried out efficiently with an alternating current, at for example, from 3,000 to 5,000 volts; the exact voltage depending on the length of the arc. The current depends on the size of the apparatus and the volume of air treated, but with the latter of constant moisture content, the amperage may be relatively small, thereby reducing retrogressive changes. Convection currents are undesirable, and the circular travel of the air, in planes at right angles to the normal axis of the arc, is important for securing a satisfactory yield. Admission of the air under a substantial pressure accomplishes the projection of an annulus of air whose particles travel in planes at right angles to the normal axis of the arc and without any

material tendency to longitudinal movement.

To recapitulate; my invention involves the production of an arc of great length, 65 capable of treating a relatively large volume of air or other nitrogen-containing gas, for the purpose of oxidizing the nitrogen thereof to a substantial extent and with a minimum of aureola contact and retrogressive 70 decomposition, characterized by the passage of the air or other gas spirally and not helically around said arc; so that the gaseous current travels in a circular path substantially in a plane at right angles to the axis 75 of the normal arc.

What I claim is:—

1. In the process of electrically oxidizing nitrogen, the step which consists in forming an annulus of nitrogen and oxygen containing gases about an arc and in causing the particles of said gases to travel in planes substantially at right angles to the normal axis of the arc, said gases being of constant moisture content. 85

2. In the process of electrically oxidizing nitrogen the step which consists in forming an elliptical annulus of nitrogen and oxygen containing gases about an arc and in causing the particles of said gases to travel in 90 planes substantially at right angles to the normal axis of the arc, said gases being of constant moisture content.

3. The process of oxidizing nitrogen which comprises forming an electric arc and 95 passing air substantially concentrically, but not helically, about said arc.

4. The process of oxidizing nitrogen which comprises forming an electric arc and passing air of constant moisture content 100 substantially concentrically, but not helically, about said arc.

5. The process of oxidizing nitrogen which comprises forming an electric arc and passing preheated air of constant moisture 105 content substantially concentrically, but not helically, about said arc.

6. The process of oxidizing nitrogen which comprises forming an elongated electric arc and passing a gaseous mixture containing nitrogen and oxygen, substantially spirally but not helically, about said arc; whereby a minimum of aureola contact and retrogressive decomposition is secured. 110

Signed at Montclair in the county of 115 Essex and State of New Jersey this 9th day of June A. D. 1911.
